DESIGN FOR A CASING FOR A COMBINED CLOCK AND RADIO

Jack Glassberg, Newark, N. J.

Application March 28, 1933. Serial No. 47,617

Term of patent 3½ years

To all whom it may concern:

Be it known that I, JACK GLASSBERG, a citizen of the United States of America, residing at Newark, in the county of Essex and State of New Jersey, have invented a new, original, and ornamental Design for a Casing for a Combined Clock and Radio, of which the following is a specification, reference being had to the accompanying drawing, forming part thereof.

The figure is a perspective view of a casing for a combined clock and radio, showing my new design.

I claim:—

The ornamental design for a casing for a combined clock and radio, as shown.

JACK GLASSBERG.
